UNITED STATES PATENT OFFICE.

MORRIS FATMAN, OF NEW YORK, N. Y.

DESIGN FOR A CLOTH FOR CLOAKING, &c.

SPECIFICATION forming part of Design No. 19,159, dated June 18, 1889.

Application filed May 18, 1889. Serial No. 311,075. Term of patent 3½ years.

To all whom it may concern:

Be it known that I, MORRIS FATMAN, a citizen of the United States, residing at New York city, in the county of New York and State of New York, have invented and produced a new and original Design for Cloth for Cloakings; and I do declare the following to be a full, clear, and exact description of the same, reference being had to the accompanying drawing, forming a part thereof, in which a face view of the cloth is represented.

The leading feature of my design consists in the representation of a series of four-leaved clover-tops arranged, successively, one after the other across the face of the cloth, thus forming bands composed of the series of four-leaved clover-top. A part of the stems of each clover-top also appears, the stem projecting toward the uppermost leaves of the clover-top next below, as shown in the ac-

companying drawing. The several bands composed, as stated, of the series of clover-tops are divided from each other by a space in which is produced stripes or lines broken or dotted.

In the drawing, A are the clover-leaves, B are the stems, and C are the stripes.

I claim—

The design for cloth for cloakings herein shown and described, the same comprising the series of four-leaved clover-tops arranged in the form of bands, and stripes between contiguous bands of clover-tops, substantially as set forth.

In testimony whereof I affix my signature in presence of two witnesses.

MORRIS FATMAN.
